UNITED STATES PATENT OFFICE.

THOMAS BRADY, OF EAST ORANGE, NEW JERSEY, ASSIGNOR TO OTIS ELEVATOR COMPANY, OF JERSEY CITY, NEW JERSEY, A CORPORATION OF NEW JERSEY.

GATE.

Application filed July 1, 1925. Serial No. 40,788.

The present invention relates to gates and particularly to gates for elevator cars.

One feature of the invention is to provide a gate which is capable of covering a 5 passageway of any width in an enclosure when in closed position and of uncovering the whole of the passageway when moved into open position.

Another feature is to provide a gate, in 10 the operation of which, danger of injury to persons is minimized.

Still another feature is to provide a gate which is positive and reliable in operation, which may be operated with a minimum of 15 effort, which is of rigid construction and which may be cheaply manufactured and installed.

Other features and advantages will become apparent from the following description, taken in connection with the accompanying drawings wherein the invention is embodied in concrete form and in which:—

Figure 1 is a view in elevation, with parts broken away, of one form of gate arranged 20 in closed position on a passenger type elevator car, the car being shown with the top removed and in section along line 1—1 of Figure 2;

Figure 2 is a plan view of the same, with 30 parts omitted in order to emphasize certain structural details, with the gate arranged in open position and with the top of the elevator car removed;

Figure 3 is an enlarged fragmental detail taken along line 3—3 of Figure 1;

Figure 4 is an enlarged fragmental detail taken along line 4—4 of Figure 1;

Figure 5 is an enlarged fragmental plan view of a portion of the gate, illustrating 40 the manner in which the gate turns around a corner;

Figure 6 is a view similar to Figure 2 of the gate arranged in open position on a freight type of elevator car;

Figure 7 is a view similar to Figure 1 of another form of gate;

Figure 8 is a view similar to Figure 4 of the gate shown in Figure 7; and

Figure 9 is an enlarged fragmental view 50 of the gate shown in Figure 7, parts being shown in section to emphasize certain structural features.

The form of gate illustrated in Figures 1 to 5 is composed of a plurality of vertical tubes 10 connected by hinge members 11.

The hinge members are preferably arranged in three rows, one row at the top of the gate, one at the bottom and one in the middle. Each hinge member comprises a yoke 12, a pair of lugs 13 extending outwardly therefrom and a similar but oppositely extending pair of lugs 14. A wider space is provided between the lugs 13 than between the lugs 14 in order to permit the lugs 14 on the adjacent hinge member to extend therebetween. Apertures 15 are provided in lugs 13 and similar apertures 16 in lugs 14. With adjacent hinge members in assembled relation, the apertures 15 and 16 are in vertical alignment so as to receive one of the tubes 10. Each hinge member is secured to a tube as by means of pins 17 extending through lugs 14. However, the hinge members are not pinned to the tubes through the lugs 13, they being free to turn at these points. In this manner each tube is hinged to its adjacent tube, with the hinges maintained in position by the pins 17.

Each tube 10 extends upwardly into a hanger, the hangers for the intermediate tubes being designated 18. As clearly shown for one of the intermediate tubes in Figure 4, a boss 20, formed on the bottom of the hanger 18, is provided with a vertical aperture 21 through which the tube 10 extends. A collar 22 is secured to the top of the tube as by threaded engagement or by a pin 23 as illustrated. This collar rests on the top of the boss 20 to form a vertical bearing for the tube. The frame of the 80 hanger is formed with a yoke portion 24 and two sides 25 and 26, the side 26 supporting the boss 20. A roller 27 is supported between the sides of the hanger as by a pivot pin 28, the pivot pin in turn being maintained in position by a pin 29. These rollers ride on the track 30. As shown in Figure 2 in a passenger type car, the track 30 extends across the front, bends at the front left-hand corner and continues along the side of the car to the rear thereof. The track may be supported in any suitable manner, as by studs 31 extending from plates 32 secured to the car at intervals along the path just described. It is to be understood 90 that, if desired, suitable reinforcements may be arranged on the car to facilitate the support of the track. This track acts both as a support and a guide for the gate.

The construction of the end hangers 19 110

is slightly modified, one of the end hangers being illustrated in Figure 3. The construction of the top of the hanger is the same as above described for one of the intermediate hangers. At the bottom however, a portion 33 of the hanger extends upwardly from the boss 34. An additional roller 35 is supported between the side 36 and portion 33 by a pin 37. For lightness 10 of construction, the frames of the intermediate and end hangers are preferably of channel shape, as indicated by the broken away portions in Figures 3 and 4 and in Figure 5.

15 The bottoms of the tubes 10 extend downwardly into a channel 38. This channel acts as a guide for the bottom of the gate, the channel being of the same contour as the overhead track 30. Flanges 40 are formed 20 on the sides of the channel, the channel being secured to the floor 41 of the car as by screws 42 extending through the channel. A plurality of apertures 43 are formed in the bottom of the channel, coinciding apertures 44 being formed in the car floor, to 25 allow dirt to fall through. Otherwise sufficient dirt or other matter might accumulate in the channel to prevent the proper operation of the gate. A false panel 45 is arranged in the car parallel with the left-hand side thereof. The panel may also extend a short distance to the right at the front of the car, as illustrated. The portions of the track 30 and channel 38 at the left front and 30 side of the car extend between the panel and the car.

35 The lugs 14 of the right-hand hinge member in each row are connected by a bumper plate 46. Bumpers 47 are secured to the 40 side of the car and disposed in the paths of these bumper plates. Similarly, the lugs 13 of the left-hand hinge members in each row are connected by a bumper plate 48. Bumpers 50 are secured to the car at the 45 rear in the paths of these plates.

It is to be understood that, if desired, the track and rollers may be arranged at the bottom of the gate with the channel disposed at the top. It is to be further understood 50 that the gate may be power or manually operated, no power means being shown for convenience of description.

With the gate arranged for manual operation and in closed position as illustrated in 55 Figure 1, to open the gate the operator may grasp one of the tubes 10, pulling the gate to the left. The left-hand tube 10 is illustrated in Figure 1 as substantially on the bend of the track. Upon movement of the 60 gate to the left, the rollers 27 and 35 of the left end hanger are guided by the track around the corner, Figure 5 illustrating the different positions which the various parts may assume. The left end hanger 19 pivots 65 on a vertical axis as its rollers turn the cor-

ner. As previously explained, the left end tube 10 is free to turn in the lugs 13 of the left end hinge members and in the hanger but the adjacent or next tube to the right is secured to the lugs 14 of these hinge members. The movement of the left end tube around the corner is permitted by the pivoting of the second tube within the apertures in lugs 13 of the adjacent or second hinge members and hanger. The successive 70 tubes, hangers and hinges act in a similar manner during the continued movement of the gate around the corner. The track 30 and channel 38 guide the gate between the side of the car and the panel 45. Upon the gate reaching its open position, it is stopped by the engagement of the bumper plates 48 and bumpers 50. It is to be understood that the bumpers are made of material suitable to absorb any shocks. The gate is illustrated in its open position in Figure 2. It is to be noted that the right-hand end tube 10 extends slightly out from behind the panel with the gate in open position. The gate 75 may be closed by reverse operation, the operator grasping the right-hand tube, pulling the gate to the right. As the gate reaches its closed position, it is stopped in a similar manner by the engagement of bumper plates 46 and bumpers 47. The rollers 35 prevent the gate from leaving the track due to faulty operation, such as lifting of the gate. These rollers and their hangers may be arranged at other points on the gate if desired.

The front portion of the false panel may be omitted if desired and the gate may be arranged to open all the way around to the side. In this event, should the car not be deep enough, the false panel, track and channel may be extended around another corner at the rear of the car so as to allow for the movement. Should the car be too deep, the bumpers 50 may be arranged on a properly located partition between the side of the car and the false panel. It is to be understood that the gate is equally adapted for the cars which are controlled by the passengers themselves.

It has been found in actual practice that the gate operates with very little noise. Due to the fact that the tubes 10 are maintained separated at all times, the danger of injury to the operator or passengers such as pinching of the hands or fingers is substantially eliminated. Furthermore due to the fact that the gate uncovers the whole of the passageway into the car when opened, the traffic may be handled with maximum despatch.

In Figure 6, the gate is illustrated as arranged on a freight type of elevator car. The structural details of the gate are substantially the same as those above described. The track 55, however, is mounted on the outside of the car, being secured in a manner similar to that above described by studs 130

and plates 32. Thus with the gate mounted on the track, the sides 26 and 36 of the hangers are on the outside. The channel 56 is illustrated at the side of the car with the flanges removed in order that the gate may be mounted outside the car without undue consumption of the hatchway space. The channel may be secured to the side of the car by studs and plates in the manner employed to secure the track. Also the outer flange of the channel in front of the car may be omitted, as illustrated. Bumpers 57 and 58 similar to those described for the passenger car may be provided if desired.

15 The gate is operated in the same manner as described for the passenger type car, the gate being illustrated in its open position. It is to be noted that, in this position, the right-hand end tube and bracket are to the left of the side of the car, thus presenting an opening of the same width as the inside of the car.

Referring to Figures 7 and 9, the gate therein illustrated for a passenger type of car, is formed of upright channel members 60 arranged with their flanges extending outwardly. As illustrated in Figure 9, except on the turn, the flanges are in abutting relation, thus presenting a closed type of gate. The channel members are joined by hinge members 61 arranged in three rows. With the exception of the right-hand hinge members of the two lower rows in Figure 7, each hinge member is formed of two spaced lugs 62 and a single lug 63 connected by the plate 64. Each hinge member in each row is secured, as by rivets 65, to one of the channel members 60. The single lug 63 on each hinge member extends between the lugs 62 on its adjacent hinge member, being joined by hinge pins extending through apertures 66 provided in the lugs. The hinge pins 67 for the two lower rows of hinge members are formed at their tops with positioning heads 68. The hinge pins 70 for the top row of hinge members are formed with flanges 71 at their bottom ends which act as supports for the gate. The hinge pins 70 extend upwardly into the hangers 18 and 19 where they are pivotally secured in the same manner as previously described for the tubes 10. Pins 72 are riveted or otherwise secured to the bottoms of the channel members 60. These pins extend into the channel 38 to guide the gate at the bottom. When the gate is closed, the right-hand channel member 60 extends partially into a channel 73 secured to the side of the car. The left-hand channel member 60 extends partially behind the front portion of the false panel 45. In this manner the passenger's view of the hatchway is completely shut off. This is of particular advantage in high speed elevator systems as visual realization of rap-

idly passing the successive floors is very annoying to some passengers. The right-hand channel member may be provided with a handle 74 to facilitate the opening and closing operation.

16 Bumper plates 75 join the lugs 62 of the left-hand hinge members 61 to engage bumpers (not shown) when the gate is moved into open position. A bumper 76 is secured to the car at the top thereof, being disposed in the path of the lug 63 of the right-hand hinge member 61. The right-hand hinge members for the middle and bottom rows are formed with the lugs 63 omitted. Bumpers 77 are arranged in horizontal alignment with the middle and lower rows of hinge members to engage the outer flange of the right-hand channel member.

Upon movement of the gate, the channel members spread apart at the turn. It is to be noted, however, that the reengagement of the channel members upon closing the gate occurs before they emerge from behind the front portion of the false panel 45. Thus injury to the operator or passengers such as might result from catching the fingers in between the channel members is prevented. With the gate in full open position, the handle 74 is just to the right of the false panel, presenting substantially a full opening. Thus with the closed type of gate also, traffic may be handled at each stop in a minimum of time.

Gates constructed in the above described manner may be designed to turn very sharp corners, the sharpness of the turn depending on the dimensions of the various parts employed. In practice a two and one-half inch radius for the curve at the corners has been found satisfactory.

As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

What is claimed is:—

1. In a gate, a hanger, an integral hinge member, a vertical member secured to and extending through said hinge member and having a swiveled connection at its upper end to said hanger, and a second vertical member extending through said hinge member and arranged to turn therein.

2. In combination, an elevator car, a track secured to said car and extending across the front and along a side thereof, and a gate comprising a plurality of supporting members having rollers arranged to ride on said track, a vertical member pivotally supported in each supporting member, said vertical

members forming the body portion of the gate, and hinge members for securing the adjacent vertical members together.

3. In combination; an elevator car having substantially a full opening across the front; a track secured to the car at the top thereof, said track extending across the front of the car, bending at one corner and continuing along one side toward the rear thereof; a gate comprising a plurality of upright tubes, a hanger for pivotally supporting each of said tubes, said hangers having rollers riding on said track, and hinge members for connecting the adjacent tubes; a channel secured to the floor of the car and extending

across the front of the car and around to said side in vertical alignment with said track, the tubes of said gate extending downwardly into said channel; and a false panel arranged to enclose said track and channel on said side of the car; the parts of the gate being constructed and arranged so that the gate completely encloses the opening at the front of the car when in closed position and, upon movement, follows the track and channel around the corner between the false panel and the side of the car. 20 25

In testimony whereof, I have signed my name to this specification.

THOMAS BRADY.
